QUENCHING PRESS

Leon D. Slade and Warner T. Cowell, Rochester,
N. Y., assignors to Gleason Works, Rochester,
N. Y., a corporation of New York

Application November 1, 1932, Serial No. 640,674

18 Claims. (Cl. 266—6)

The present invention relates to quenching presses and particularly presses for quenching gears or similar articles, after heat treatment, for the purpose of hardening the same.

The primary object of the present invention is to provide a quenching press in which a substantially uniform initial quench can be produced whereby substantially uniform results may be obtained in the quenching operation.

10. Further objects of the invention are to provide a quenching press in which the articles to be treated can be centered more accurately, in which without use of any more power, a greater pressure can be applied to the articles during quenching, and in which there are no moving parts under the quenching fluid so that water can be used just as satisfactorily as oil for a quenching medium. To these ends, it is a purpose of the invention to provide a quenching press in which the quenching operation is effected by passing a liquid over the article to be quenched instead of immersing it in a liquid and in which, consequently, the article to be treated can be secured on a fixed support or die.

25. Another object of the invention is to provide a quenching press in which the article to be treated is clamped by pneumatic pressure during the quenching operation and a liquid is used for the quenching medium and in which the clamping and quenching operations are controlled from a single valve.

30. A further object of the invention is to provide a quenching press in which the flow of the quenching medium is controlled from the operation of clamping the article to be quenched so that the article must be first held rigidly against distortion before the quenching medium can flow around the article.

35. Still another object of the invention is to provide a quenching press in which the amount of liquid required for the quenching operation is reduced to a minimum and the flow of the liquid is shut off automatically as soon as the article being treated is released.

40. Other objects of the invention will appear hereinafter from the specification and from the recital of the appended claims.

In the drawings:

45. Figure 1 is a side elevation of a quenching press built according to a preferred embodiment of the present invention, certain of the parts being shown in section;

50. Figure 2 is a vertical sectional view of this press, the view being in a plane extending at

right angles to the plane of the drawing in Figure 1; and

5. Figures 3 to 6 inclusive are sectional views showing, respectively, possible forms of a small reducing valve, of a whistle valve, of a large reducing valve, and of an air-operated pressure regulator which may be employed on the press.

The quenching press illustrated in the drawings is made in two main sections, a lower section or base 10 and an upper section or standard 11. 10 The base is hollow and a container or chamber 12 is mounted centrally therein. This container is adapted to hold compressed air under pressure. It is secured to the base 10 of the press by bolts 13 and its upper end is closed by a plate 14 15 that is held in place by bolts 15.

The base is formed with an integral chamber 16, the side walls 17 of which are spaced from the outside walls 18 of the base. Openings 20 are cut at spaced intervals in the side walls 17 20 of the chamber 16 so that the chamber 16 communicates with the hollow chamber 22 that is enclosed by the outer walls of the base and is formed between the walls 17 and 18.

At some distance above the top wall 23 of the 25 chamber 16, the base is provided with an integral internal flange or ring 24. There is a supporting plate 25 secured to the flange 24 by screws 26. This supporting plate 25 carries the seat member 27 and this in turn carries a plate 28. The plate 30 28 carries a single ring member or the plurality of nested ring members 29 which constitute the lower die supporting the article to be quenched. The lower die also carries the expansible gripping device which is adapted to engage the bore 35 or interior of the article to be quenched to hold the article true during the quenching operation.

In the drawings, we have shown the press arranged to quench a spiral bevel gear G and the 40 expansible gripping device may be made of a plurality of independently movable segmental grippers 30 of the same type as described in the patent to Leon D. and Alton P. Slade, No. 1,166,307 of January 26, 1915.

The supporting plate 25 and the rest 27 are 45 each provided with a circularly arranged series of openings, the openings in the supporting plate being designated at 32, while those in the rest 27 are designated at 33. Each opening 32 in the supporting plate 25 aligns with an opening 33 in 50 the rest 27. The plate 28 is provided with a circular series of openings 36, which are much smaller in diameter than the openings 33, but which communicate with the openings 33. The plate 28 and the lower die members 29 are also 55

provided with a series of communicating radial slots 37 which communicate with the openings 36. The slots 37 lead in under the gear to be quenched so that the quenching medium can flow from the chamber 22 through the openings 32, 33 and 36 and ducts 37 in under the gear.

The supporting plate and rest are also provided with central openings 34 and 35, respectively, which align with one another and with the central opening 39 formed by the segmental grippers 30, when assembled. Hence the quenching medium can also flow from the chamber 22 through the openings 34, 35 and 39 over and around the gear.

15 The base 10 is formed at its top with an annular ring or flange 40. This is spaced far enough above the flange 24 so that a well is formed in the base which contains the lower die, the expandable gripping device and the gear to be quenched.

15 The standard 11 is secured to the flange 40 above the well 42 by bolts 41. The standard 11 carries a cylinder 43, which is secured in place on the standard by bolts 44. The upper end of 20 the cylinder 43 is closed by an end-plate 45, which is secured in position by screws 46, while the lower end of the cylinder is closed by an end-plate 47 which is secured in position by screws 48.

25 There is a hollow piston 50 mounted in the cylinder 43 to reciprocate therein. The upper end of this piston 50 is closed by a plate 52 that is formed with a central recess. The end-plate 45 that closes the upper end of the cylinder 43 is provided with a central tubular projection 53 through which compressed air is supplied to the upper end of the piston 50 to move the piston downwardly in the cylinder. The projecting conductor 53 of the plate 45 is received in the central recess of the plate 52 when the piston 50 is at the upper limit of its movement in the cylinder 43. The piston-rings 54 which prevent leakage of air along the piston 50 are held in place by the ring 55 which is secured to the piston by screws 56. The plate 52 is held in position by screws 58.

30 The lower end of the piston 50 is closed by a plate 60. This plate 60 is formed at its lower end with a seat for the die-support 62. The plate 60 and die-support 62 are secured to the piston 50 by screws 63.

35 The upper die 64 is secured to the lower face of the die support 62 by bolts 65. This upper die will be shaped, as is the usual practice, to engage the upper end or face of the article to be quenched.

40 The upper die support 62 has a conical outer surface and is centrally bored to provide a cylinder 66. The piston 67 is mounted in this cylinder to reciprocate therein. The plate 60 closes the upper end of the cylinder 66, while a plate 68 is secured to the lower face of the support 62 to limit downward movement of the piston 67 in the cylinder 66. The plate 68 is held in position by screws 69.

45 A tapered expander 70 for operating the grippers 30 is secured in any suitable manner to the piston 67. A centering stud 72, that has a pressed fit in a recess in the plate 60, extends centrally through aligned openings in the piston 67 and expander 70.

50 There is a plate 74 spaced below the plate 60 and secured thereto by studs 75. This plate serves as an outboard guide or support for the piston 50 in its movement.

55 The pistons 50 and 67 are preferably operated

by pneumatic pressure, while a liquid medium is employed for the quenching operation. The manner in which the piston 50 is actuated and the manner in which the quenching medium is applied to the gear or other article to be treated will now be described.

60 Compressed air is supplied to the press from any convenient source through the pipe 89 (Figure 1). At the press, the compressed air passes first through a strainer 81 which may be of any suitable construction and which is designed to remove dirt or grit from the air line.

65 After leaving the strainer 81, the air line divides. Part of the air passes through the T 82 and connecting piping into a large reducing valve 84 (Figures 1 and 5) and part passes from the T 82 through the pipe 85. The reducing valve 84 controls the pressure exerted by the upper die on the body of the gear or other article being treated.

70 The reducing valve 84 may be of any suitable construction. A valve of one standard make is illustrated simply as an aid to a better understanding of the operation of the press.

75 The compressed air enters this reducing valve 84 through the duct 87. The inner end of this duct is normally closed by the valve 83 that is carried by a double-armed member 89. The member 89 is secured at its upper end to a flexible diaphragm 90. The valve 83 is normally held shut by the action of the coil springs 92 and 93, the tension of which can be adjusted by the screw 94. A more detailed description of the construction of the valve 84 need not be given here, since the valve forms no part of the present invention. As long as the pressure in the air line is great enough, the valve 83 is held open and the air can flow from the reducing valve line 87 out of the port 95 into the line 96.

80 The valve 84 is connected by the pipe 96 and the T 97 with a standard pressure gage 98. The pressure of the air flowing from the reducing valve 84 is recorded on this gage and hence the gage can be used to determine the pressure at which the reducing valve can be adjusted to open.

85 From the T 97, the compressed air flows through the pipe 99 to a four-way valve 100 which may be of any suitable construction. This valve is operated by the lever 101. It is connected by the pipe 102 with the lower end of the cylinder 43 and by the piping 104 with the upper end of this cylinder. The fourth line 105 leading from this valve is an exhaust line and may either be opened to the air or be connected to the compressor employed to compress the air for use in the system.

90 When the lever 101 is turned in one direction, pressure is applied to the upper end of the piston 50 to lower the upper die 64 upon the article to be quenched, and when the lever 101 is reversed, pressure is applied to the lower end of the piston 50 to raise this piston in the cylinder 43 and withdraw the upper die from engagement with the work.

95 The upper end of the piston 67 is always on pressure when the machine is in use. The compressed air is conducted to the upper end of this piston from the line 25 already referred to, through the connection 110, the line 111, a small reducing valve 112, and ducts 125, 126 and 127, to which further reference will be made herein-after.

100 This reducing valve 112 may be of any suitable construction. One possible construction is shown in Figure 3, in which there is illustrated

the construction of a standard valve now in common use. This valve controls the pressure exerted on the bore of the gear or other article being quenched. The valve is normally open, the valve proper 113 being normally held off of its seat 114 by the pressure of the coil spring 115 that operates against a flexible diaphragm 116 to which the stem of the valve 113 is connected. The tension of the spring 115 can be adjusted by manipulation of the screw 118.

There is a pressure gage 120 of standard construction connected to the valve 112. This gage records the pressure of the air passing through the valve 112. By adjusting the screw 118 and checking against this gage, the valve 112 can be adjusted so that the proper pressure is secured on the upper end of the piston 67. If the pressure entering the valve chamber 112 is excessive, the pressure of the air on the diaphragm 116 will close the valve proper 113. The air may enter the valve chamber 112 at 122 and leave through the opening 123.

The valve 112 is connected with the gage 120 by the T 125. This T is connected with a second T 126 and this latter T is connected through the flexible hose 127 and the duct 128 with the upper end of the cylinder 65. The duct 128 is formed in the plate 60. The T 126 is also connected by a pipe 130 with a relief-valve 131. This relief-valve may be of any suitable construction and has not been illustrated in detail, as such valves are in common use.

When the press is ready for operation, the chamber 12 in the base will be filled with air under a definite pressure and the chambers 16 and 22 in the base will be filled with oil or water or whatever quenching liquid is employed in the press. When the piston 50 has descended and the upper die 64 is exerting such a pressure upon the body of the work and the grippers 30 such a pressure upon the bore of the work as to hold the gear against distortion, the air in the chamber 12 is discharged into the chamber 16. In the chamber 12, this air will have been under a very high pressure. In the chamber 16 it will expand rapidly and will rapidly force the quenching liquid from this chamber and from the chamber 22 up through the openings 32—33—36 and 34—35—39 in and around the gear to be quenched, producing an initial drastic quench.

The supply of air to the chamber 12 is controlled by a whistle valve which may be of any suitable construction. One possible construction is shown in section in Figure 4. This valve, which is designated at 135, is operated by the upper die support 62 in its movement. The operating lever 136 of the valve is arranged to engage the conical outer surface of the upper die support. The coil spring 137 operating on the valve 138 proper tends to keep the valve closed. When the piston 50 is raised to the upper limit of its movement, however, the lever 136 is rocked about its pivot 139 and the nose 140 of this lever through its engagement with the valve stem 141 forces the valve 138 open. This allows air to flow into the chamber 12. When the upper die support 62 descends, however, the valve is again closed by the spring 137 and the supply of air to the chamber 12 is shut off.

The air comes to the valve 135 through the line 85 already referred to, the connection 119, a pressure reducing valve 145 which may be identical in construction with the valve 112 and the lines 146 and 147.

From the whistle valve 135, the air passes to the chamber 12 through the lines 148 and 149, the T 150, and the lines 151, 152, 153, 154, 155, and 156, and the duct 157. The duct 157 is drilled in the bottom wall of the chamber 12. The pressure reducing valve 145 controls the pressure of the air in the chamber 12. A standard pressure gage 158 which is connected to the T 150 records the pressure in the chamber and is used to adjust the valve 145 to secure the desired pressure.

The flow of air from the air-chamber 12 into the liquid chamber 16 is controlled by a direct-acting three-way valve 160 which may be of any suitable construction. The valve shown in section in the drawings is connected by the lines 161 and 162 with the line 154, already mentioned, that leads into the chamber 12. The valve 160 is also connected by a line 163 with a pipe 164 that is mounted in the upper part of the chamber 16. The pipe 164 is provided with a plurality of holes 20 or openings 165 through which air can escape into the chamber 16 when the air chamber 12 is connected with the chamber 16. The third line 167 leading from the valve 160 is an exhaust line.

The valve 160 comprises the valve proper 170 whose stem threads into a head 172. A coil spring 173 which surrounds the valve stem serves to normally hold the valve 170 against its upper seat, as shown in the drawings, thus closing the line 161 and connecting the line 163 with the exhaust line 167. The valve 160 is adapted to be operated by air pressure. When compressed air under sufficient pressure is admitted into the valve 160 above the head 172, the valve 170 is forced downward, opening the line 161 and closing the line 35 167. This puts the line 163 on supply from the line 161. The structure and operation of the valve 160 need not further be described because such valves are well known and the valve itself forms no part of the present invention.

The supply of quenching liquid to the chambers 16 and 22 is controlled by a direct-action three-way valve 175, which may be larger than the valve 160 but of similar construction. The supply of quenching liquid comes to the press from any suitable source, as a tank or reservoir, through the pipe-line 177. The quenching liquid enters the press through the pipe-line 178. This line, as does the line 163, threads into the plate 179 that closes an opening in one side wall 18 of the base of the press and that forms part of one side wall of the chamber 16. The plate 179 is secured in position by bolts 180.

The third line from the valve 175 is an exhaust line comprising the piping 182 and 183. The two 55 lines 167 and 183 are connected by a T 184. This T is in turn connected through suitable connections with the main exhaust line 185.

The coil spring 187 which surrounds the stem of the valve proper 188, serves to normally hold the valve 188 in the upward position shown in the drawings with the line 178 cut off from supply. The valve 175 is intended, however, to be operated by air pressure and when a sufficient pressure is applied to the head 189 of the valve stem, the valve proper 188 is forced down from its upper seat to its lower seat, thus opening the line 178 to supply from the line 177 and closing the exhaust line 182.

The valves 160 and 175 are intended to be operated by pneumatic pressure built up in the cylinder 43 after the upper die 64 has engaged the work. There is a line 190 which is connected to a T 191 that is incorporated in the line 104. The 75

line 190 is connected through a T 192, line 193 and T 194 with a line 195 that leads into one side of an air-operated pressure regulator 196. The pressure regulator may be of any suitable construction. That shown in the drawings is a regulator of well-known make. It includes a cam 197 that is rotatably mounted on an arm 198 which is pivotally mounted at 199 in the casing of the regulator. The periphery of the cam contacts 10 with one side of a capsular chamber 200 to which the line 195 is connected. The cam also engages the stem of a valve 201 which is kept closed by the coil spring 202.

The valve 201 controls communication between 15 a line 202 and a line 203. The cam 197 is adjustable by rotation to determine what amount of pressure on the capsule 200 shall be required in order to open the valve 201. For convenience in adjusting the cam 197, the regulator 196 is 20 provided with a hand 204 (Figure 1) that is secured to the shaft that carries the cam 197. This hand 204 reads against a graduated dial on the gage.

The amount of pressure in the lines 190—195 25 is recorded by the gage 206 which may be of standard construction and which is connected to the T 192.

When the pressure in the line 195 is great 30 enough to open the valve 201, the compressed air passes from the line 85 through the connection 190, the line 210, a pressure reducing valve 212, which may be of the same construction as the valve 112, the lines 213 and 202 to the line 203. The pressure in the lines 213 and 202 is determined 35 by the setting of the pressure reducing valve 212 which is recorded on the gage 215. This gage, which may be of standard construction, is connected to the lines 210 and 213 by the T 216.

The compressed air entering the line 203 operates a direct-acting three-way valve 220, which 40 is smaller than the valves 160 and 175, but which may be similar in construction to them. The spring 222 of the valve 220 normally acts to shut off connection between the lines 224 and 225. 45 When the valve 201 is opened, however, the compressed air flowing from the line 202 through the line 203 will operate the valve 220 against the resistance of the spring 222 and the lines 224 and 225 will be connected. Then the compressed air flowing from the line 213 through the T 223 into 50 the line 224 will pass into the line 225 and through the lines 226 and 227, which are connected with the line 225 by the T 228, to the valves 160 and 175, respectively.

The pressure in the line 224 is determined by 55 the adjustment of the reducing valve 212 and can be read on the gage 215 which is connected to the lines 210 and 213 by the T 216. The reducing valve 212 will be adjusted so that sufficient pressure will be obtained in the line 224 and, therefore, in the lines 226 and 227 to operate the valves 160 and 175, respectively, while protecting these valves against excessive pressure.

The valve 220 is closed at its bottom by a plug 60 229 and there is no exhaust line leading from this valve.

To use the press, the operator selects a lower 65 die 29 whose upper surface is shaped to conform to the shape of the lower face of the gear or other article to be treated. Likewise, an upper die 64 is selected, shaped to engage the upper face of the article to be treated. The two dies serve to press and to hold the article in correct shape during the quenching operation. The grippers 30 are selected in accordance with the diameter of the bore or

of the interior of the gear or other article to be quenched.

Before using the press, the operator also adjusts the valves 112, 131, 84, 145, 196 and 212. The valve 112 is adjusted in accordance with the maximum pressure which it is desired to have exerted on the bore of the gear during the quenching operation. The relief valve 131 is adjusted to blow off at a pound or so above this maximum pressure. If too great a pressure is applied to the bore of a gear during hardening, the bore will open up in the hardening. The valve 84 is adjusted in accordance with the pressure which it is desired to have exerted on the body of the gear by the upper die. This pressure wants to be high enough to press and hold the gear in correct shape. The valve 145 is adjusted in accordance with how drastic an initial quench is desired, for the adjustment of this valve predetermines the maximum pressure of the air in the chamber 12. 20 This pressure is naturally varied for gears of different section and different diameter.

The valve 196 predetermines the pressure which it is desired to have exerted on the body of the gear before the valve 160 can be opened to allow 25 the air to pass from the chamber 12 into the liquid reservoir 16. The valve 212 acts simply as a safety valve to prevent too high a pressure being applied to the valves 228, 160 and 175. These valves are built to open at a definite pressure and an excessive pressure might have a deleterious effect upon them.

Assuming that the air-chamber 12 has been filled with air under a predetermined pressure and that the reservoirs 16 and 22 are filled with 30 quenching liquid, the press is ready for operation.

In the operation of the press, the article to be treated, such as the gear G, is first placed, while hot, upon the lower die 29. The operator then 40 turns the lever 131 of the four-way valve 109 so as to admit compressed air into the cylinder 43 above the piston 50 and at the same time to put the lower end of the cylinder 43 on exhaust. This causes the piston 50 to descend in the cylinder 43 45 and lower the upper die 64 upon the work.

As previously stated, the upper end of the piston 67 is always on pressure from the supply line 80 through the lines 85 and 111, the reducing valve 112, the T's 125 and 126, the piping 127 and the 50 duct 128. Thus, as the piston 50 descends, the pilot member 72 and taper expander 70 will come into engagement with the grippers 30 before any substantial pressure is exerted by the upper die upon the gear. The pilot 72 serves to center the 55 grippers 30 and the expander 70 serves to expand them to engage the bore of the gear and round the same up. As the piston 50 continues to descend, the small piston 67 will be forced upwardly in its cylinder 66 against the resistance of the 60 air. This will build up pressure in the upper end of this piston. This built-up pressure will hold the expander in operative position throughout the quenching operation, but if the pressure rises too high, the relief valve 131 will blow off.

When the upper die comes into contact with the body of the gear, the large piston 50 is stopped. This causes pressure to be built up in the upper end of the cylinder 43 and in the lines 104, 190 and 195. When this pressure is great enough, it 70 will operate the pressure regulator 196 opening the valve 201, thus permitting the compressed air to flow from the supply line 80 through the lines 85 and 210, the reducing valve 212 and the lines 213, 202 and 203 to the three-way valve 220. This 75

causes this valve to be opened so that the compressed air can flow from the line 213 through the lines 224 and 225 to the lines 226 and 227 opening the valves 160 and 175.

5 As soon as the valve 160 is opened, the compressed air in the chamber 12 rushes out of this chamber through the duct 157 and the lines 156, 155, 154, 161 and 163 into the pipe 164 and out through the openings 165 in this pipe into the reservoir 16. The pressure of the air escaping through the openings 165 causes the quenching liquid to be forced out of the reservoirs 16 and 22 through the openings 32, 33 and 36 and the slots 37 under the gear and through the openings 15 34 and 35 and the opening 39 between the expander members 30 to flow between the teeth of the gear. Thus the hot gear is quenched and hardened.

The rush of air from the chamber 12 into the chamber 16 is so rapid, when the valve 160 is opened, that the quenching liquid in the reservoirs 16 and 22 is very rapidly forced around the gear and an initial drastic quench is the result. The set of the gear in a quenching operation is of course produced by the initial quench. With the present press, a uniform volume of liquid is moved by a uniform volume of air to effect the initial quench. Hence uniform results are naturally obtained.

30 The valve 175 is opened at the same time as the valve 160 so that quenching liquid can flow into the press from the line 177 through the line 178. In use, the upper die is allowed to remain down for a substantial period after the initial drastic quench and the liquid entering the press from the pipe 177 flows up around the gear and thoroughly cools it. The liquid which flows around the gear after the initial quench has, however, no appreciable effect on the hardness or internal structure of the gear. The set of the gear, as stated before, is produced by the initial drastic quench.

The overflow liquid from the well 42 is carried away through the pipe 230 which is connected to the well and which leads back to the tank from which the liquid is drawn by the pipe 177.

After the gear has been sufficiently cooled, the operator reverses the lever 101, thus putting the lower side of the piston 50 on supply and the upper side on exhaust. The lines 190 and 195 being connected to the line 104 are also put on exhaust with the result that the valve 201 is closed by the spring 205. The valves 160 and 175 are therefore closed under actuation of the springs 173 and 181, respectively. Thus the flow of the quenching liquid into the press is shut off as soon as the upper die starts to leave the work and the air in the lower part of the press is exhausted from the reservoir 16 through the pipes 164, 163, 167 and 185.

The whistle valve 135 will have remained closed during the descent of the upper die upon the gear and during the time of quenching, but as the piston 50 rises, the conical outer surface of the upper die support 62 engages the operating lever 136 of the whistle valve, forcing the valve open against the resistance of the spring 131. This enables the chamber 12 to be refilled with compressed air, for when the whistle valve is open, the compressed air will flow from the supply line 80 through the lines 85, 146, 147, 148, 151, 152, 153, 154, 155, and 156 and the duct 157 into the chamber 12. The whistle valve remains open as long as the piston 50 is in its upper po-

sition, as illustrated in Figure 2. The pressure of air in the chamber 12 is governed by the adjustment of the reducing valve 145. This valve closes the line to the chamber 12 from the supply line 80 when the pressure of air in the chamber 12 is at the operating pressure desired.

When the piston 50 has been raised far enough, the hardened gear can be taken out of the press and another hot gear put in its place to be quenched.

10 The skirt 232 that is secured to the upper die support 62 by screws 233 is for the purpose of confining the quenching liquid about the gear during the quenching operation, so as to secure the maximum cooling effect from this liquid. It cooperates for this purpose with the rest 21.

15 By constructing the press so that the valves 160 and 175 cannot be opened until a sufficient pressure is built up in the upper end of the cylinder 43 to operate the pressure regulator 196, assurance is had that the gear or other article to be quenched is held rigidly in proper shape before the cooling or quenching operation can start.

20 The pressure of the air in the chamber 12 can be varied to suit the character of the article being quenched. A much lower pressure can be used in the press of the present invention than is required in presses where the work is submerged in the quenching medium.

25 Another feature of the press shown is the use 30 of a stationary lower die. With such a die, all the pressure exerted on the upper end of the piston 50 is applied directly to the gear throughout the whole of the quenching operation, whereas in presses where the work is submerged, the pressure on the work is effected by the movement of the lower die until the work has been submerged. The use of a stationary lower die has the further advantage of enabling gears to be held more rigidly so that they come from the 35 press flatter on the bottom and truer in the bore than with presses where the work is submerged. A further advantage of the press with the stationary lower die is the fact that there are no 40 moving parts under the quenching liquid. Hence 45 even water may be used as a quenching medium without danger of rust affecting the life of the press.

50 While the invention has been described in connection with a particular embodiment and with 50 a particular use for this embodiment, it will be understood that the invention is capable of further modifications and uses and that this application is intended to cover any adaptations, uses, or embodiments of the invention following, 55 in general, the principles of the invention and including such departures from the present disclosure as come within known or customary practice in the art to which the invention pertains and as may be applied to the essential features hereinbefore set forth and as fall within the 60 scope of the invention or the limits of the appended claims.

Having thus described our invention, what we 65 claim is:

1. In a quenching press, a stationary work support, a source of supply for the quenching liquid, a valve normally preventing flow of liquid from said source of supply to the work, pneumatically-operated means for clamping the work on said support, pneumatically-operated means for opening said valve, and means connecting the second pneumatically-operated means to the first so that the second is operated by rise of pressure 70 75

- in the first when the work is clamped on said support.
2. In a quenching press, a support for the article to be quenched, a cylinder, a piston movable therein under pneumatic pressure, a die secured to said piston and adapted to clamp the article to be quenched on said support when said piston is moved in one direction in said cylinder, a source of supply of the quenching liquid, a normally closed pressure operated valve for controlling flow of liquid from said source of supply to the article to be quenched, said valve being connected to said piston so as to be opened when the pressure on said piston holding the die in clamping position reaches a predetermined amount and to be closed when the pressure on said piston falls below said predetermined amount, and means controlling the direction of application of fluid pressure to said piston.
3. In a quenching press, a stationary work support, a reservoir for the quenching liquid, ducts connecting said reservoir with the work support, a normally closed chamber adapted to contain a definite volume of a gas under pressure, means for clamping an article on the work support, means for supplying gas to said chamber, means operable to shut off said gas supply and means operable, after said gas supply has been shut off, to connect said chamber with said reservoir to force quenching liquid out of said reservoir through said ducts by gas-pressure.
4. In a quenching press, a stationary work support, a reservoir for the quenching liquid, ducts connecting said reservoir with the work support, a normally closed chamber adapted to contain a definite volume of a gas under pressure, means for clamping an article on the work support, means for supplying gas to said chamber, means operable to shut off said gas-supply, and means operable automatically after an article has been clamped on the work support and after said gas-supply has been shut off, to connect said chamber with said reservoir to force quenching liquid out of said reservoir through said ducts by gas-pressure.
5. In a quenching press, a support for the article to be quenched, a reservoir for the quenching liquid, a chamber adapted to contain air under pressure and adapted to be connected with said reservoir to enable the air to force liquid from said reservoir around the article to be quenched, a source of air supply, a reciprocable member for clamping the article on said support, and a three-way valve controlled by the reciprocation of said member to admit air from said chamber to said reservoir when said clamping member has been moved to clamping position and to reconnect said chamber with the source of air supply when said clamping member is moved to inoperative position.
6. In a quenching press, a support for the article to be quenched, a reservoir for the quenching liquid, a chamber adapted to contain a definite volume of gas under a definite pressure, a source of supply for the quenching liquid, pressure operated means for clamping an article on said support, pressure operated valve for controlling admission of gas from said chamber into said reservoir, and a pressure operated valve controlling flow of liquid from said source of supply to said reservoir, and means operatively connecting said valves to said clamping means so that said valves are operated by rise of pressure on the clamping means when an article is clamped on said support.
7. In a quenching press, a stationary support for the article to be quenched, a clamping member for securing said article on said support, a source of supply for the quenching liquid, a normally closed air-pressure operated valve controlling flow of the quenching liquid from said source around said article, air pressure operated means comprising a cylinder and a piston reciprocable therein for moving the clamping member to and from operative position, and a duct connecting said valve with the side of said piston which is on pressure when the clamping means is moved to clamping position, whereby, when the article is clamped on the support under a predetermined pressure, the back-pressure in said duct will open said valve.
8. In a quenching press, a stationary support for the article to be quenched, a clamping member for securing said article on said support, a reservoir containing a definite amount of quenching liquid, a chamber adapted to contain a definite volume of air under pressure, a normally closed air-pressure operated valve controlling flow of air from said air chamber to said reservoir, ducts leading from said reservoir around the article to be quenched, means comprising a cylinder and a piston reciprocable therein for moving the clamping member to and from operative position, and a duct connecting said valve with the side of said piston which is on pressure, when the clamping member is moved to clamping position, whereby, when the article is clamped on the support under a predetermined pressure, the back-pressure in said duct will open said valve.
9. In a quenching press, a chamber adapted to contain a definite volume of compressed air, a reservoir adapted to contain a definite volume of the quenching liquid, a stationary support for supporting the article to be quenched above the normal level of liquid in said reservoir, ducts connecting the reservoir with the support to conduct liquid from said reservoir to an article mounted on said support, a normally closed valve controlling the connection between said chamber and said reservoir, means for clamping an article on said support, and means automatically responsive, when the article is clamped at a predetermined pressure, to open said valve to permit flow of the compressed air from said chamber into said reservoir to force the liquid out of said reservoir through said ducts and around said article.
10. In a quenching press, a chamber adapted to contain a definite volume of compressed air, a reservoir adapted to contain a definite volume of quenching liquid, a stationary support for supporting the article to be quenched above the normal level of liquid in said reservoir, ducts connecting the reservoir with said support to conduct liquid from said reservoir around an article mounted on said support, means for clamping an article on said support, and a normally closed valve operable by said clamping means for controlling flow of air from said chamber to said reservoir.
11. In a quenching press, a stationary work-support, a reservoir adapted to contain quenching liquid, a chamber adapted to contain a definite volume of gas under a definite pressure, ducts for conducting liquid from said reservoir to the work, a valve controlling connection of said chamber with said reservoir, pneumatically-operated means for clamping the work on said support, pneumatically-operated means for op-

erating said valve, and means connecting the two pneumatically operated means together so that the second is operated by rise of pressure in the first when the work is clamped on said support.

12. In a quenching press, a stationary work support, a reservoir for the quenching liquid, ducts for conducting liquid from said reservoir to the work support, a chamber adapted to contain a definite volume of gas under pressure, a connection for supplying gas to said chamber, a movable member for clamping an article on the work support, means for closing the connection between said chamber and the source of gas-supply when the clamping member is moved to clamping position, and means for connecting said chamber to the reservoir when the article is clamped on said support.

13. In a quenching press, a stationary work support, a reservoir for the quenching liquid, ducts for conducting liquid from said reservoir to the work support, a chamber adapted to contain a definite volume of gas under pressure, a connection for supplying gas to said chamber, a movable member for clamping an article on the work-support, means for automatically closing the connection between said chamber and the source of gas-supply when the clamping member is moved to clamping position, and means for automatically connecting said chamber to said reservoir when the article is clamped on said support under a predetermined pressure.

14. In a quenching press, a stationary work-support, a reservoir adapted to contain quenching liquid, ducts for conducting liquid from said reservoir to the work support, a connection for supplying liquid from a source of liquid-supply to said reservoir, means normally closing said connection, a chamber adapted to contain a definite volume of gas under pressure, a connection for supplying gas to said chamber, a movable member for clamping an article on the work support, means for automatically closing the connection between said chamber and the source of gas-supply, when the clamping member is moved to clamping position, means for automatically connecting said chamber to said reservoir when the article is clamped on said support under a predetermined pressure, and means for simultaneously opening the connection between said reservoir and the source of liquid-supply.

15. In a quenching press, a stationary work support, a reservoir adapted to contain quenching liquid, ducts for conducting liquid from said reservoir to the work support, a chamber adapted to contain a definite volume of gas under pressure, a connection for supplying gas to said chamber from a source of gas supply, a movable member for clamping an article on the work support, a valve for controlling the connection of the chamber with the source of gas supply and operatively connected to said movable clamping member to be open when said clamping member is in released position and closed when the clamping member is moved to clamping position, and means operatively connected to said movable member for connecting said chamber to said reservoir when the article is clamped on the work support under a predetermined pressure.

16. In a quenching press, a stationary work support, a reservoir adapted to contain quenching liquid, a connection for supplying liquid from a source of liquid-supply to said reservoir, a valve normally closing said connection, ducts for conducting liquid from said reservoir to the work

support, a chamber adapted to contain a definite volume of gas under pressure, a connection for supplying gas to said chamber from a source of gas-supply, a movable member for clamping an article on the work support, a valve for controlling the connection of the chamber with its source of gas-supply and operatively connected to said movable clamping member to be open when said clamping member is in released position and closed when the clamping member is moved to clamping position, means operatively connected to said clamping member for connecting said chamber to said reservoir when an article is clamped on the work support under a predetermined pressure, and means also operatively connected to said movable member for simultaneously opening the first named valve when the article is clamped on the work support under the specified pressure.

17. In a quenching press, a frame, a stationary work support secured to the frame, a cylinder and a piston one of which is fixed relative to the frame and the other of which is movable, means secured to the movable part for clamping an article on the work support, a reservoir adapted to contain quenching liquid, ducts for conducting liquid from said reservoir to the work support, a chamber adapted to contain a definite volume of gas under pressure, a normally closed pressure-operated valve controlling flow of gas from said chamber into said reservoir, a duct connecting said valve with the side of the piston which is on pressure when the clamping member is moving to clamping position whereby when an article is clamped on the work support under a predetermined pressure, the back-pressure in said duct will open said valve, a second valve controlling connection of the chamber with the source of gas-supply, and means operatively connecting said second valve with the movable clamping member to close said valve on movement of the clamping member to clamping position and open said valve when the clamping member is withdrawn from clamping position.

18. In a quenching press, a frame, a stationary work support secured to the frame, a cylinder and a piston one of which is fixed relative to the frame and the other of which is movable, means secured to the movable part for clamping an article on the work support, a reservoir adapted to contain quenching liquid, ducts for conducting liquid from said reservoir to the work support, a chamber adapted to contain a definite volume of gas under pressure, a connection between said reservoir and a source of liquid-supply, a connection between said chamber and the reservoir, a pair of pressure-operated valves controlling, respectively, the connection between the reservoir and its source of liquid-supply and the connection between the chamber and the reservoir, means operatively connecting said valves with the side of the piston which is on pressure when the clamping member is moving to clamping position whereby when an article is clamped on the work support under predetermined pressure the back-pressure will open said valve, a third valve controlling connection of the chamber with a source of gas-supply, and means operatively connecting said third valve with the movable clamping member to close said valve on movement of the clamping member to clamping position and open said valve when the clamping member is withdrawn from clamping position.
